Design No 752.

Joseph W Gardner's Design For

Hives and Tools.

Patented Dec. 25th 1855.

UNITED STATES PATENT OFFICE.

JOSEPH W. GARDNER, OF SHELBURNE FALLS, MASSACHUSETTS, ASSIGNOR
TO LAMSON, GOODNOW & CO.

DESIGN FOR A TABLE KNIFE AND FORK.

Specification forming part of Design No. 752, dated December 2nd, 1855.

To all whom it may concern:

Be it known that I, JOSEPH W. GARDNER, of Shelburne Falls, in the county of Franklin and State of Massachusetts, have invented or produced a new and original Design for Knives and Forks; and I do hereby declare that the following is a full and exact description thereof, having reference to the accompanying drawings, and to the letters of reference marked thereon.

A is the handle, and B the bolster, in Figures 3 and 4, of a knife, and, Figs. 1 and 2, of a fork. The next section in all forks and extension-knives heretofore made is that termed by manufacturers the "neck," which said neck is in this design entirely dispensed with, thereby reducing the cost of manufacture in each of the processes of forging, grinding, polishing, and burnishing, and at the same time producing a new and original as well as symmetrical shape or configuration of both knives and forks. The shank C arises from the crown b of the bolster B, and, extending longitudinally, it diminishes in both its diameters by graceful internal curvatures throughout nearly its entire length, the form of its cross-section being in this example that of a diamond, as shown at s,

with the exception that the angles are slightly flattened at the points marked c. This neckless shank is in all respects appropriate for both knives and forks by properly joining the same to the blade E of the knife or with the bosom D of the fork. For knives the shank C terminates at and joins to the blade E by two short curves toward the back and edge of said blade, and the angles of the sides of the shank C are continued nearly or entirely through said curves, as shown in Figs. 3 and 4. For forks the angles of the sides of the shank C are continued upon the sides of the bosom D, and, gradually diminishing, terminate nearly opposite the base of the prongs F, thus forming, as set forth, a new, original, and symmetrical design for the purposes as described.

I make no claim to anything respecting the parts A, B, D, E, or F; but

What I do claim is—

The part marked C, substantially as set forth.

JOSEPH W. GARDNER.

Witnesses:

ARTHUR MAXWELL,
GUY H. HUBBARD.
